SPARK ARRESTER FRAME FOR
LOCOMOTIVES

Benjamin H. Pedigo, Jackson, Tenn.

Application February 16, 1945, Serial No. 578,222

5 Claims. (Cl. 110—122)

1

This invention relates to spark arresters for boilers and particularly locomotive boilers, and is an improvement over the construction embodied in my prior Patent No. 1,652,580 dated December 13, 1927, for Netting door for locomotive smoke boxes.

An object of this invention is to provide an improved netting or screen for holding the sparks and hot cinders from being discharged through the stack.

Another object of this invention is to provide a netting or screen of this character which is self-cleaning.

A further object of this invention is to provide a netting or screen of this kind which includes removable panels with each panel formed of a pair of screens so that a selected screen section may be easily removed for replacement or the like.

A further object of this invention is to provide an improved means for locking the removable panels or frames to the stationary supporting frame, so that the removable panels will be held against warping.

To the foregoing objects, and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawings:

Figure 1 is a fragmentary vertical sectional view taken longitudinally through a locomotive boiler having a spark arrester mounted therein, constructed according to an embodiment of this invention.

Figure 2 is a sectional view taken on the line 2—2 of Figure 1.

Figure 3 is a fragmentary sectional view similar to Figure 2 with the screen frames removed.

Figure 4 is a sectional view taken on the line 4—4 of Figure 1 or Figure 2.

Figure 5 is a fragmentary sectional view taken on the line 5—5 of Figure 2.

Figure 6 is a fragmentary sectional view taken on the line 6—6 of Figure 2.

Figure 7 is a fragmentary sectional view taken on the line 7—7 of Figure 2.

Figure 8 is a fragmentary sectional view taken on the line 8—8 of Figure 2.

Figure 9 is a fragmentary sectional view taken on the line 9—9 of Figure 4.

Figure 10 is a fragmentary plan view of the 55

nozzle and the frame supporting structure mounted thereon.

Referring to the drawings, the numeral 15 designates generally a cylindrical boiler designed for a locomotive, which is provided with a nozzle 16 and a smoke stack 17 above the nozzle 16, which is formed with a flared lower intake end 18.

The boiler 15 includes a smoke box 19, and in order to provide a means whereby the sparks entering the smoke box 19 will be prevented from passing upwardly through the flared intake 18 and the smoke box 17, I have provided a removable screen structure which includes outer side screen members 20 and 21 and intermediate or central screen or door structure 22. The screens 20, 21 and 22 are removably mounted on a stationary frame structure which is secured within the boiler 15 and includes oppositely disposed longitudinally curved bars 23 and 24 which are welded to the inner side of the boiler 15. The boiler 15 includes a baffle, or dead plate, 31 of conventional design and location, so located to direct the smoke and gases to the outer and central screen structures 20, 21, and 22.

25 An upper plate 25 is disposed above the upper ends of the outer side bars 23 and 24, being disposed in a vertical position, whereas the frame bars 23 and 24 are disposed on a downward and inward inclination. A horizontally extending bar 26 is formed integral with the plate 25, being bent inwardly on the same angle as the inclination of the frame bars 23 and 24. The frame bar 23 is provided with a plurality of elongated openings 27 positioned inwardly from the outer edge thereof, and the frame bar 24 is formed with a plurality of elongated openings or keepers 28, positioned inwardly from the outer edge thereof. A lower horizontally disposed frame bar 29 is disposed across the lower portion of the boiler 15 40 and terminates at the opposite ends thereof at the inner edges of the side frame bars 23 and 24.

The opposite ends of the frame bar 29 are free from the outer side bars 23 and 24, so that when desired the lower frame bar 29 may be removed. 45 The frame bar 29 is secured, as by welding or the like, to a supporting ring 30, which engages over the tapered upper end 31 of the nozzle 16. The lower frame bar 29 has projecting forwardly and downwardly therefrom lugs 32, 33 and 34, the 50 purpose for which will be hereinafter described.

The lug 32 has secured thereto an upwardly and forwardly projecting pin 35, and the lug 33 has secured thereto an upwardly and forwardly projecting pin 36. The lug 34 has projecting therefrom an upwardly and forwardly extending

pin 37, and the latter is formed, as shown in Figure 9, with a transverse opening 38. The side screen frame 20 comprises a lower frame bar 39, which is adapted to engage against the forward side of the lower frame bar 29 and the screen structure 20 also includes an outer longitudinally arcuate frame bar 40 disposed in confronting position to side frame member 23. The screen structure 20 also includes an inner frame bar 41 and an upper frame bar 42. The frame bars 39, 40, 41 and 42 are secured together in any suitable manner, as by welding, or the like, and an angularly disposed bracing bar 43 is secured between the frame bars 40 and 41 and is formed with a plurality of openings 44 through which the smoke and gases are adapted to pass. A wire screen 45 is secured to the inner side of the frame structure formed by the bars 39, 40, 41 and 42 by means of bolts or other fastening devices 46. In this manner the screen 45 may be taken off from the frame when this screen becomes damaged or burnt in any portion thereof.

In order to provide for supporting and locking the screen structure 20 to the boiler, I have provided a plurality of substantially L-shaped lugs 47, which are carried by the outer frame member 40, and are adapted to extend into the openings 27 of side frame member 23. The lugs 47 are formed with downwardly directed bills 48, so as to firmly lock the screen frame structure with respect to the side frame bars 23. The slots 27 are of sufficient length to permit the free passage of the locking and supporting members 47 therethrough.

The upper frame bar 26 has secured thereto a screen frame supporting hook 49, which is similar to the construction shown in Figure 6. There is one hook for each of the screen frames and these hooks are of like construction. These hooks are formed of an upwardly bent or substantially L-shaped hook 49, which is formed with one or more stepped portions 50 with which the upper frame bar 42 is adapted to engage, the latter being formed with a slot 51 for passage of the hook 49.

The lower end of the screen frame structure 20 is provided with a forwardly and downwardly extending lug 52, having an opening 53 through which the pin 35 is adapted to extend. The inner frame 41 has extending forwardly therefrom a plurality of spaced apart upwardly directed and substantially L-shaped locking members 54, which are adapted to engage through slots 55 formed in the adjacent side bar 56 of the central screen structure or door 22. The central screen structure or door 22 is of rectangular configuration and includes opposite side bars 56 and 57 and upper and lower bars 58 and 59. A V-shaped bracing member 60, which is formed with openings 61, is secured between the opposite side bars 56 and 57. The lower bar 59 is provided with a forwardly and downwardly extending lug 62, having an opening 63 through which the pin 37 is adapted to engage, and a locking wedge or bolt 64 engages through the slot 38 and bears against the upper side of lug 62, so as to firmly lock the central door with respect to the lower frame bar 20.

A chain 65 is secured at one end to the wedge or key 64, and is secured at the opposite end thereof to the lower end of pin 37 so that the key will not be lost when it has been withdrawn, or in the event it should accidentally become disengaged from the opening 38 in pin 37.

The upper frame bar 58 is provided with a slot or opening 66 through which the supporting hook 75

49 is adapted to engage. The opposite side frame 21 is constructed similar in every detail to the side frame 20, being formed of an outer longitudinally curved bar 67 secured between upper and lower bars 68 and 69, and the latter have secured therebetween an inner side frame bar 70. An angularly and apertured bracing bar 71 is secured between the side bars 67 and 70. The outer side bar 67 is formed with a plurality of downwardly directed and substantially L-shaped hooks 72 which engage through the slots 28 for locking the frame structure formed by the bars 67, 68, 69 and 70, relative to the boiler 15.

The upper bar 68 is formed with an elongated slot 72a for receiving the supporting hook 49 associated with this outer side frame and the inner frame bar 70 has projecting forwardly therefrom a plurality of upwardly directed center door supporting hooks 73, which are similar to the hooks 54 shown in Figure 8. The center door side bar 51 is formed with a plurality of slots 74, through which the supporting hooks 73 are adapted to engage, and as will be noted from Figure 2, the side bars 56 and 57 of the center door overlap the adjacent side bars 41 and 10, respectively, of the side screen structure.

With a construction as hereinbefore described, the side screen structures cannot be removed until the center door or screen structure has been removed. The center door frame structure includes a wire screen 75 secured to the inner side of the frame structure by bolts 76, or the like, and the side frame structure 21 includes a wire screen 77 secured to the frame structure thereof by bolts or other suitable fastening members 78.

In the use of this spark arrester structure, the stationary frame members 23, 24 and 25 are welded, or otherwise firmly secured to the inner side of the boiler wall and the lower frame member 29, which is a removable frame member, is mounted on the upper end of the nozzle 16 by means of the supporting ring 30. The outer screen structures 20 and 21 are initially inserted by engaging the structures with the hooks 49, carried by the frame bar 26, and engaging the lug 52 of screen structure 20 with pin 35.

Screen structure 21 has projecting forwardly and downwardly therefrom a lug 79, having an opening 80 through which the pin 36 is adapted to engage. The center door may then be engaged with the upwardly directed hooks 54 and 73, and also engage with the associated upper hook 49, which extends through the slot 66 of upper frame bar 58 and lug 62 is extended over pin 31. Key 64 is then inserted in keeper slot 38.

What I claim is:

1. In a conventional locomotive boiler having a firebox and a smoke box, means communicating with the firebox through its rear wall and with said smoke box for directing the smoke from the firebox to said smoke box, a smokestack extending through the top wall of said smoke box, a nozzle through the bottom of said smoke box aligning with the smokestack, and a baffle secured at its top edge to the top of the smokebox within the smokebox between the stack and nozzle and the point at which the smoke directing means communicates with the smoke box, the side walls of said baffle being secured to the side walls of the smokebox extending downwardly and forwardly from said top edge to a point forwardly of the nozzle, said baffle surrounding the nozzle and having its free edge spaced above the bottom of the smokebox whereby to provide a passageway for the gases of combustion therebeneath and up around said

free edge to the stack, a spark arresting means comprising a stationary screen supporting frame disposed in said smokebox, said frame comprising an upper bar fixed within the smokebox to the top thereof forwardly of the stack and nozzle transversely of the smokebox, a pair of opposed side bars extending downwardly from said first bar in contact with the sides of the smokebox to the free edge of the baffle, said side bars being formed with spaced apart elongated slots, a lower horizontal bar extending between the lower ends of said side bars and connected to said free edge of the baffle, means removably supporting said lower bar from said nozzle, screens across the space between the bars and the free edge of the baffle, said screens comprising opposite side screen members, outwardly extending hooks relative to one face of the side screens carried by the outer portions of said side screen members and engageable in said slots for detachably securing said side screen members to said frame, outwardly extending hooks relative to the other face of the side screens carried by the inner portions of said side screen members, and said screens also comprising a central screen member formed with spaced slots in the opposite side portions thereof for receiving said upwardly directed hooks to thereby detachably secure said central screen member to said side screen member.

2. A spark arrester as set forth in claim 1, including apertured bracing bars carried by said side and central screen members. 80

3. A spark arrester as set forth in claim 1, including correlated means carried by said lower frame bar and said side and central screen members for detachably securing said screen members to said lower frame bar.

4. A spark arrester as set forth in claim 1, including outwardly extending hooks relative to one face of said upper frame bar carried by said frame bar, said screen members being formed with slots for receiving said latter hooks for detachably coupling said screen members to said upper bar.

5. A spark arrester as set forth in claim 1, wherein said lower bar supporting means includes a ring fixed to said lower bar and engaging about said nozzle.

15 BENJAMIN H. PEDIGO.
